MULTICOLOR CINEMATOGRAPHY METHOD

Pierre Juillet, Albon, France

Application October 13, 1947, Serial No. 779,499
In France October 23, 1946

6 Claims. (Cl. 88—16.4)

1

My invention relates to cinematography in natural colours and more particularly to the methods wherein the different hues of the image seen by the observer result from the addition of a number of primary colours (generally three, sometimes only two).

In these methods there is projected on the cinematographic screen a number of successive images taken through monochromatic filters, the said images being coloured by passage of the projected rays through coloured filtering screens identical to the said filters. These successive images are seen by the observer as a single image in natural colours.

When the images of a colour cycle (which will be supposed hereinafter to comprise three primary colours) are taken simultaneously, the film speed through the projecting apparatus is to be multiplied by three with respect to the usual speed of the white-and-black cinematography if the same impression of continuity in the motion of objects is to be preserved. This leads in practice to the projection of 72 images per second, which is too much for most existing apparatus adapted for the standard speed of 24 images per second.

When the three images of a cycle are taken successively, the film speed has not to be increased and may remain at the usual standard of 24 images per second, but the successive images are no more identical and they do not combine correctly for objects in motion. The edges of such objects therefore appear as formed of the three primary colours in juxtaposition (as in a rainbow), which is a material drawback.

It has also been proposed to project simultaneously on the screen the three images of a colour cycle, the said images being exactly superposed. If these images have been taken simultaneously, this method avoids all the above inconveniences, but it requires delicate apparatus and much skill to obtain exact registration of the three elementary images on the screen.

Moreover the known methods require that the three images of a cycle should be taken exactly from the same point, since these three images are to be exactly identical apart from the colour. When such is not the case, the objects taken at short distance give rise to images which do not fully register on the screen which again produces coloured edges.

A first object of my invention is to avoid coloured edges on moving objects or on objects at short distance from the camera.

My invention relates to a method wherein there

2

are projected at the same time on the screen two elementary images in juxtaposition, these images being of different colour and the colour of each image following the selected cycle of primary colours during the successive projection of pairs of images, while the said images are observed by the observer by means of a selecting device transmitting to each eye only one image, in the manner known in stereoscopy.

10 It will readily be understood that the two elementary images of a pair of images are seen by the observer as a single image, the colours of which result from the addition of the primary colours of the elementary images of the pair under consideration. During the projection of the successive pairs of images the observer thus sees a succession of images and perceives a single moving image in natural colours finally resulting from the addition of all the elementary colours.

15 In the usual case of three primary colours, if 1, 2, 3, designate the primary colours, the successive pairs of images may be represented by 1—2, 2—3, 3—1, 1—2 and so on, or 1—3, 2—1, 3—2 and so on.

20 Each elementary image thus passes through the whole cycle of colours and would by itself ensure the perception of natural colours. But owing to the juxtaposition of two images at the same time on the screen, the speed of combination of elementary colours is much higher than in the known processes. In the usual case of three elementary colours and with a film speed of 24 images per second, it takes $\frac{1}{4}$ of a second

25 to have a full cycle of images. In my method a pair of images such as 1—3 will appear on the screen during substantially $\frac{1}{4}$ of a second. The duration of a luminous perception on the human eye being at least $\frac{1}{16}$ of a second, the observer will still see the said pair during $\frac{1}{16} - \frac{1}{4} = \frac{1}{48}$ of a second, that is during one half of the time of projection of the next pair formed of images 2—1. Thus the combination of primary colours will be perfected within $\frac{1}{16}$ of a second against $\frac{1}{4}$ in the known methods. The drawback of coloured edges will be reduced to a minimum since moreover two elementary images will be seen simultaneously.

30 According to a characteristic feature of my invention the combination of colours is much improved by projecting each elementary image successively in two colours which give by additive combination the primary colour in which this image has been taken in the camera, the second one of these two colours being the first one used for the projection of the same image in the next

pair of elementary images, all as more fully explained below.

My improved method is more particularly of advantage in the case of stereoscopic cinematography since it then permits to obtain natural colours almost without any additional apparatus. The distance between the two points from which the elementary stereoscopic images are taken does not give rise to coloured edges since each elementary image passes through the full cycle of colours in the successive pairs of images.

In the annexed drawings:

Fig. 1 illustrates a cinematographic film according to my invention in a three-colour system.

Figs. 2 and 3 diagrammatically show in elevation and in plan view two devices for the projection of such films.

Fig. 4 is a front view of a coloured filter disc used for taking views in a three-colour system.

Fig. 5 is a front view of an adjustable circular screen for the projection of a three-colour film.

Fig. 6 is a longitudinal section thereof.

Fig. 7 is a diagrammatical elevation illustrating a device for the observation of the projections.

Fig. 8 is the corresponding plan view.

Fig. 9 is a diagrammatical illustration of a camera for the obtention of a film of the kind of Fig. 1.

The film of Fig. 1 carries a succession of pairs of elementary images taken through three different colour filters according to the three-colour system. These images are disposed, one above the other in each pair. The successive pairs have been referenced I, II, III and so on, while the images are referenced 1, 2 or 3 according to the primary colour to which they correspond. It will be observed that each image of the pairs, for instance the upper one, is successively 3, 1, 2 and so on in the successive pairs, while the lower one is 1, 2, 3, the successive pairs being 1-3, 2-1 and 3-2. It will be observed that the colour cycle comprises three pairs and six images.

The images, taken through appropriate monochromatic filters in a manner per se well-known, might be coloured on the film itself; but this would involve considerable difficulties and it is preferable to use filtering screens in the projecting apparatus, these projection screens carrying the same colours as those used in combination with the camera.

Fig. 2 illustrates such an arrangement comprising a rotary disc 10 disposed between the film 11 to be projected and the projecting lens 12. This disc is provided with transparent coloured areas forming filtering screens for the rays emanating from the film. It comprises a coloured portion for each film image and must be disposed close to the film to avoid that rays from a film image may pass through the filtering area corresponding to the other image. There is obtained on the projection screen a pair of coloured images disposed one above the other.

Fig. 3 illustrates a modified arrangement comprising two projecting lenses 12' and 12'' each adapted to receive selectively the rays from one film image. The bundle of rays from each image is reflected twice by a double prism 13' or 13'', whereby lenses 12' and 12'' may be disposed in rather spaced relation. In such a case the filtering disc 10 may be placed in front of the lenses as illustrated.

The filtering disc should of course rotate in

synchronism with the film advancing gear and it must be provided with a number of pairs of coloured areas corresponding to a whole number of colour cycles.

Fig. 4 illustrates a filtering disc for a three-colour system, its coloured areas corresponding to the film images of Fig. 1. It comprises three sector-shaped pairs of coloured areas, which have been referenced after the colours to which they correspond.

It will be evident that the disc of Fig. 4 effects one rotation for three film advancing motions. In other words the disc effects one rotation for each whole cycle of the image pairs on the film. It would of course be possible to devise discs effecting one rotation for any whole number of such cycles, as will be apparent for any one skilled in the art.

In accordance with my invention, in a three-colour system, each image is projected in two successive colours, different from the primary colour to which it corresponds, but so selected that their combination reproduces this primary colour. Supposing for instance that the primary colours are, as usually, red, yellow and blue, instead of projecting the image corresponding to the red through a red filtering screen during the whole projection period of $1/24$ of a second, it is successively projected through an orange filtering screen during $1/48$ of a second and through a violet screen during another $1/48$ of a second. The observer perceives an image coloured in red. In the same manner the image corresponding to the yellow will be projected through orange and green screens, while the image corresponding to the blue will be projected through green and violet screens.

It will be remarked that there is thus obtained another regular cycle of three colours: Orange, green and violet. In addition each image in the successive pairs is projected at the beginning of a projection period in the same colour as at the end of the preceding period. For instance the upper image will be projected as follows: first period, violet and orange; second period orange and green; third period, green and violet; and so on. In other words the change of colour is effected between the successive changes of pair of images. This leads to a remarkable feeling of continuity for the observer.

Figs. 5 and 6 illustrate a gearing adapted for such a method. The coloured areas 1, 2 and 3 cover practically the whole circular development of the disc 10 as against the disc of Fig. 4. The disc is driven by means of a planetary mechanism embodying a sun wheel 14 keyed on the actuating shaft 15 rotating in synchronism with the film advancing gearing, planet gears 16 carried by a support 17, and an internally toothed crown wheel 18 mechanically in one with disc 10. Support 17 is keyed on a shaft 19 frictionally locked by a spring 20, but adjustable in angular position by means of a knob 21.

This disc operates in combination with the usual shutter of the projection apparatus and it is so disposed that during a projection period the rays from the film images pass successively through two successive pairs of coloured areas such as 1-3 and 2-1, for instance. By operating knob 21 it is possible to adjust at will the timing of the passage from one pair of coloured areas to the next one and to correct any defect which might appear on the projection screen in the hues of the pictures.

It will be apparent that any gearing with three members in mutual connection (mechanisms with three degrees of freedom) may be substituted for the planetary gearing described. For instance there might be employed the well-known differential gearing used in automobiles.

Figs. 7 and 8 diagrammatically show how the images projected on the projection screen may be observed. There is disposed in front of each eye a double reflecting device 22' or 22'' enabling the eye to see only one image and these two devices are adjusted until the two virtual images perceived by the observer are in perfect registration forming a single image in natural colours.

Fig. 9 illustrates an arrangement for obtaining the negative film by means of which positive films such as those of Fig. 1 may in turn be obtained. This arrangement comprises two lenses 23' and 23'' disposed one above the other, two double reflecting prisms 24' and 24'', and a filter disc 10 rotating in front of lenses 23' and 23''. This arrangement is quite similar to the projecting device of Fig. 3.

In my improved method there exists a certain difference between the images of a pair owing to the distance apart of the two lenses 23' and 23'' (difference in space or space parallax). But this defect does not exist between the successive upper (or lower) images since they are taken with one and the same lens. There also exists a certain difference between the successive upper (or lower) images since they correspond to successive moments, that is to successive positions of moving objects (difference in time or time parallax). But this defect does not exist between the two images of each pair which are taken simultaneously.

It will thus be understood that the importance of the above defects is quite reduced. Coloured edges are practically unapparent.

My invention is of particular advantage in combination with stereoscopic cinematography employing elementary images in juxtaposition on the projection screen, since it then only requires the use of filter discs without any modification of the apparatus.

It will moreover be understood that the above description has been given merely by way of example and that it does not limit my invention as defined by the appending claims. The images have been shown as disposed one above the other, but they could also be arranged side by side.

I claim:

1. A method for cinematography in natural colors which consists in recording on a cinematographic film a succession of monochromatic images of the object according to a first cycle of three primary colors; and in projecting said images on a screen in proper succession while imparting to each in succession two colors of a second cycle of three primary colors, the said two colors being such that they give by additive combination the primary color in which the image has been recorded, and the last one of these two colors being the same as the first one imparted to the next image occupying the same place on the projection screen.

2. In a method as claimed in claim 1, the step of adjusting the respective durations of projection of each image in each primary color of said second cycle.

5 3. A method for cinematography in natural colors which consists first in recording on a cinematographic film successive pairs of juxtaposed monochromatic images of the object, the two images of each pair being taken simultaneously 10 in different primary colors and each image in the successive pairs passing successively through a first cycle of three primary colors; second in projecting the said pairs of images in succession on a projection screen, the images of each pair being simultaneously projected on the screen in close but spaced relation; third in imparting in succession to each projected image two colors of a second cycle of three primary colors, the said two colors being such that they give by additive 15 combination the primary color in which the image has been recorded, and the last one of these two colors being the same as the first one imparted to the next image occupying the same place on the projection screen.

20 4. In a method as claimed in claim 3, the step of adjusting the respective durations of projection of each image in each primary color of said second cycle.

25 5. In a method for cinematography in natural colors by successive projection of monochromatic images corresponding to a predetermined cycle of three primary colors, the step of projecting each image through two successive coloured filters the colors of which give by additive 30 combination the primary color of said predetermined cycle of colors to which this image corresponds, the second used of said coloured filters being the same as the first used for projection of the next image occupying the same 35 place on the projection screen.

40 6. In a method as claimed in claim 5, the step of adjusting the respective durations of projection of each image through each of said coloured filters.
